(57) **CLAIM**

The ornamental design for cosmetic button, as shown and described.

DESCRIPTION

FIG. 1 is a perspective view of cosmetic button, showing the front and right sides and top thereof, and showing the new design;

FIG. 2 is another perspective view thereof, showing the front and right sides and top thereof, and viewing the top more directly than in FIG. 1;

FIG. 3 is a top plan view of said cosmetic button;

FIG. 4 is a perspective view thereof, showing the rear and left sides and top thereof;

FIG. 5 is another perspective view thereof, showing the rear and left sides and top thereof, and viewing the rear side more directly than in FIG. 4;

FIG. 6 is a front elevational view of said cosmetic button;

FIG. 7 is a left-side elevational view thereof, the left side being a mirror image of the right side thereof; and,

FIG. 8 is a rear elevational view of said cosmetic button.
